Primary Examiner — Robert M. Spear*Assistant Examiner* — John A Voytek(74) *Attorney, Agent, or Firm* — Middleton Reutlinger(57) **CLAIM**

The ornamental design for a toilet, as shown and described.

DESCRIPTION

FIG. 1 is a front perspective view of a toilet design;
FIG. 2 is a front elevation view of the design of FIG. 1;
FIG. 3 is a rear elevation view of the design of FIG. 1;
FIG. 4 is a top plan view of the design of FIG. 1;
FIG. 5 is a bottom plan view of the design of FIG. 1;
FIG. 6 is a left side elevation view of the design of FIG. 1;
and,
FIG. 7 is a right side elevation view of the design of FIG. 1.
The broken lines illustrating portions of the toilet form no part of the claimed design.

1 Claim, 7 Drawing Sheets(56)
